UNITED STATES PATENT OFFICE.

ALBERT H. SHERWOOD, OF OROVILLE, CALIFORNIA.

ADJUSTABLE COPY-HOLDER.

1,265,396.

Specification of Letters Patent.

Patented May 7, 1918.

Application filed October 23, 1917. Serial No. 198,012.

To all whom it may concern:

Be it known that I, ALBERT H. SHERWOOD, a citizen of the United States, residing at Oroville, in the county of Butte and State 5 of California, have invented new and useful Improvements in Adjustable Copy-Holders, of which the following is a specification.

This invention relates to an adjustable 10 copy holder for typewriters.

One of the objects of the present invention is to provide a simple form of copy holder for typewriters which may be readily applied to or removed from the carriage of 15 the typewriter, and which is so constructed that the sheet to be copied may be quickly inserted and adjusted with relation to a reading slot formed in the holder. Another object of the invention is to provide means 20 for automatically feeding or advancing the holder in unison with the movement of the platen so that line after line will move into register with the reading slot as the work progresses. Further objects will hereinafter 25 appear.

The invention consists of the parts and the construction and combination of parts as hereinafter more fully described and claimed, having reference to the accompanying 30 drawings in which—

Figure 1 is a front view of the upper part of a typewriter, showing the application of the invention.

Fig. 2 is a side elevation of same.

Fig. 3 is a central, longitudinal section through the copy holder.

Fig. 4 is a cross section of same.

Fig. 5 is a side elevation of the spreader.

Referring to the drawings in detail, A indicates the upper portion of the main frame 40 of a typewriter, 2 the carriage proper, 3 the tracks upon which the carriage is supported, 4 the platen, 5 the spacing lever, 6 the pawl on the inner end of the spacing lever, 45 and 7 the toothed ratchet or spacing wheel secured on the end of the platen. Suitably secured at each end of the carriage is a socket member 8, and adapted to be received by each socket member is a bracket 50 arm 9, one being provided for each socket.

These socket members 8 serve as supports for a holder, generally indicated at 10.

This holder 10 is constructed of tin, aluminum, or other suitable sheet-like material. It is approximately semicircular in 55 cross section and the front portion is pro-

vided with a reading slot 11. Adapted to be supported on the holder 10 is a cylinder 12, which is constructed of glass, celluloid or any other transparent or semi-transparent material. Secured on each end of the cylinder 12 is a bearing ring 13, and formed on the outer end of one of said rings is a plurality of ratchet teeth 14. Pivotedly mounted, as at 15, on one of the brackets 9 60 is a pawl 16, and adapted to hold one end of said pawl in engagement with the spacing pawl 6 is a spring 17. The lower end of the pawl 16 passes directly under the spacing pawl 6, while the upper end 18 assumes a position which permits it to engage with the teeth 14 formed on the bearing ring 13 of the copy holder 10.

The cylinder 12 is provided for the purpose of receiving the sheet to be copied. 75 This sheet is merely inserted in the cylinder from either end and when so inserted is held against the inner face of the cylinder by means of a spreader 19. This spreader consists of a ring 20 and two pairs of U- 80 shaped cross spring arms 21, that is, insertion of the spreader in either end of the cylinder, after a sheet has been inserted, spreads the sheet or holds it in contact with the inner face of the cylinder, thus preventing it from collapsing and at the same time supporting it in a position where the typed or written matter contained thereon may be easily read through the reading slot 11. 85

The copy holder proper or the cylinder 12 may be lifted out of the holder or may be left in the holder when a sheet is to be inserted or removed. A pin 22, secured in the receiver 10, engages with the end bearing ring at the point shown in Fig. 3, thereby preventing the pawl member 18, when engaging the teeth, from moving the cylinder endwise or displacing it with relation to the reading slot 11. The cylinder is otherwise entirely free and independent as regards the receiver 10 and may, therefore, be quickly removed or replaced when desired. It is otherwise perfectly free to rotate in the receiver, and one of the features of the 100 present invention is to provide means for automatically rotating the cylinder while the typing or copying of the sheet is taking place, so that line after line will automatically move into register with the reading 105 slot while the work is proceeding.

This is accomplished by transferring the

movement of the platen, through the pawl 16, to the cylinder. For instance, if the spacing lever 5 is rocked to rotate the platen one space, then it can readily be seen that the pawl 6 will engage the lower end of pawl 16 and also cause this to rock and bring the pawl into engagement with the teeth 14 and thereby rotate this one space. If the spacing lever is operated for two spaces a similar transfer will take place, while three spaces permit a triple spacing or movement of the copy holder or cylinder 12.

If it is desired to double space the copy which is being typed on the sheets placed on the platen and it happens that the data on the copy holder in the cylinder 12 is single spaced, then it is only necessary to depress the pawl 16 one space by inserting a pin 24 in a plate 25 forming part of the bracket arm 9. This depression of the pawl 16 one space permits the pawl 6 to move one space without engaging the pawl 16, while the remaining movement of the pawl 6 will engage the pawl 16 and move it one space. A double spacing of the sheet placed on the platen 4 can, therefore, take place while a single space only is transmitted to the copy holder. The pin 24 may be raised or lowered in openings formed in the plate so that it also becomes possible to triple space the platen and single space the copy holder or to triple space the platen and double space the copy holder. This is of considerable importance as it sometimes happens that the sheet to be copied is single or double spaced, while the sheet to be typed should be double or triple spaced.

While the pawl 16 serves as a means for automatically turning the copy holder in unison with the platen and also permits a lost motion between the platen and copy holder, I do not wish to limit myself to the specific mechanism shown as other makes of typewriters may require a considerable variation in construction. The important feature involved is the provision of the receiver 10 and a copy holder supported therein.

The sheet to be copied may be inserted within the cylinder where it is transparent or it may be suitably attached to the outside of the cylinder, if desired, thereby permitting an opaque or semi-transparent material to be used. The bearing rings 13 provided serve as a means for retaining the cylinder 12 out of contact with the surface of the receiver, thereby preventing the surface of the cylinder from becoming scratched or soiled through constant rotation and use of same.

The materials and finish of the several parts of the device may be such as the experience and judgment of the manufacturer may dictate.

I wish it understood that various changes

in form, proportions, and minor details of construction may be resorted to within the scope of the appended claims and that I do not wish to limit myself to the specific design and construction here shown.

Having thus described my invention, what I claim and desire to secure by Letters Patent is—

1. A copy holder for typewriters comprising a receiver secured to and adapted to travel with the carriage of the typewriter, a transparent, cylindrical member supported in the receiver, said cylindrical member adapted to receive the copy to be re-typed, and a spreader comprising a ring having a plurality of spring arms secured thereto adapted to be placed endwise within the cylindrical member to support the copy against the inner face of the cylindrical member.

2. A copy holder for typewriters comprising a receiver secured to and adapted to travel with the carriage of the typewriter, a transparent, cylindrical member supported in the receiver, said cylindrical member adapted to receive the copy to be re-typed, means for securing the copy against the inner surface of the cylindrical member, and a bearing ring secured on each end of the cylindrical member.

3. A copy holder for typewriters comprising a receiver secured to and adapted to travel with the carriage of the typewriter, a transparent, cylindrical member supported in the receiver, said cylindrical member adapted to receive the copy to be re-typed, means for securing the copy against the inner surface of the cylindrical member, a bearing ring secured on each end of the cylindrical member, and means engageable with one of the bearing rings to lock the cylindrical member against endwise movement in one direction.

4. The combination with the carriage, the platen and the spacing lever on a typewriter, of a receiver secured upon the carriage, a cylindrical copy holder supported by the receiver, a bearing ring on each end of the cylinder, teeth cut in the end of one of said rings, and a pivotally mounted lever engageable at one end with said teeth and at the opposite end with a pawl operated by the spacing lever.

5. A copy holder for typewriters comprising a trough-shaped receiver secured to and adapted to travel with the carriage of a typewriter, a transparent, hollow, cylindrical member adapted to be laid in the trough, said cylindrical member adapted to receive therein the copy to be re-typed, means for securing the copy against the inner surface of the cylindrical member, means for transmitting movement from the spacing lever on the typewriter to rotate the cylinder, a bearing ring on each end of the cylinder adapted to hold the transparent cylinder out of con-

tact with the trough, and means for locking the cylinder against movement in one direction.

6. A copy holder for typewriters comprising a trough-shaped receiver secured to and adapted to travel with the carriage of a typewriter, a tubular transparent copy holder adapted to lie in the trough, said tubular transparent copy holder having its ends open and unobstructed, means for securing the copy to be re-typed against the inner surface of the tubular member, a plurality of ratchet teeth formed on one end of the tubular member, a lever pivotally mounted on the carriage engageable at one end with said teeth to rotate the tubular member within the trough, means for securing the tubular member against endwise movement in one direction, and means connecting the opposite end of the lever with a pawl operated by the spacing lever on the typewriter to permit rotation of the tubular member when the platen on the typewriter is rotated.

7. A copy holder for typewriters comprising an open-ended trough-shaped receiver secured to and adapted to travel with the carriage of a typewriter, a transparent hollow cylindrical member adapted to be laid and to rest in the trough, the ends of said cylinder being entirely open and unobstructed to permit the free insertion therein of the copy to be re-typed, means for securing the copy against the inner surface of the cylindrical member, means for transmitting movement from the spacing lever on the typewriter to intermittently rotate the cylinder while it is resting in the trough and means for locking the cylinder against movement in one direction.

8. A copy holder for typewriters comprising an open-ended trough-shaped receiver secured to and adapted to travel with the carriage of a typewriter, a transparent hol-

low cylindrical member adapted to be laid 45 and to rest in the trough, the ends of said cylinder being entirely open and unobstructed to permit the free insertion therein of the copy to be re-typed, means for securing the copy against the inner surface of the 50 cylindrical member, a plurality of ratchet teeth formed on one end of the cylinder, said teeth projecting outwardly in alignment with the surface of the cylinder, a spring pawl engageable with said teeth, means for 55 transmitting movement from the spacing lever on the typewriter to rock said pawl and means for locking the cylinder against endwise movement in the trough in one direction.

9. A copy holder for typewriters comprising an open-ended trough-shaped receiver secured to and adapted to travel with the carriage of a typewriter, a transparent hollow cylindrical member adapted to be laid 65 and to rest in the trough, the ends of said cylinder being entirely open and unobstructed to permit the free insertion therein of the copy to be re-typed, means for securing the copy against the inner surface of the 70 cylindrical member, means for transmitting movement from the spacing lever on the typewriter to intermittently rotate the cylinder while it is resting in the trough and means for locking the cylinder against movement 75 in one direction, said means comprising a bearing ring secured on each end of the cylinder and a projection formed in the trough engageable with one of said bearing rings.

In testimony whereof I have hereunto set my hand in the presence of two subscribing witnesses.
